UNITED STATES PATENT OFFICE.

EDMUND C. BATES, OF ALLIANCE, OHIO, ASSIGNOR TO THE BUCKEYE JACK MANUFACTURING COMPANY, OF ALLIANCE, OHIO, A CORPORATION OF OHIO.

LIFTING-JACK.

1,230,818.

Specification of Letters Patent. Patented June 19, 1917.

Application filed September 16, 1914. Serial No. 862,005.

To all whom it may concern:

Be it known that I, EDMUND C. BATES, a citizen of the United States, residing at Alliance, in the county of Stark and State 5 of Ohio, have invented certain new and useful Improvements in Lifting-Jacks, of which the following is a specification.

The invention relates to jacks having ratchet teeth on the side of the lifting bar, 10 and a pair of pawls operating in alternate engagement therewith for lifting and lowering the bar; and the object of the improvement is to provide simplified and efficient means for controlling the action and 15 operation of the reversing lever employed in jacks of this type.

The object of the invention is attained by providing a torsion spring having one of its ends extended to form an elongated 20 finger in sliding engagement with one end of the reversing lever, for holding the same either in or out of its proper position for reversing the operation of the jack, and at the same time permitting the lever to yield 25 in the performance of its reversing action.

A preferred embodiment of the invention is illustrated in the accompanying drawings, forming part hereof, in which—

Figure 1 is a perspective view of the lifting jack, with one side plate omitted to show details of the operating elements;

Fig. 2, a fragmentary side elevation of the same; and

Fig. 3, a fragmentary perspective view of a modified form of the controlling spring.

Similar numerals refer to similar parts throughout the drawings.

The base 1 of the jack is provided with the upright standard 2, in which is formed 40 a guideway for the lifting bar 3 having the rest 4 on its upper end and the ratchet teeth 5 on one side.

The operating lever 6 is fulcrumed on the pivot 7 mounted in the standard, on which 45 pivot is also mounted one of the pawls 8, while the other pawl 9 is mounted on the inner end 6^a of the lever by means of the pivot 10; the pawls 8 and 9 being adapted to alternately engage the ratchet teeth on 50 the side of the lifting bar for the purpose of raising or lowering the same in the manner well known in the art.

The reversing lever 11 is mounted on the pivot 12 on the side of the standard, adjac- 55 ent to and preferably below the pivot 7 of

the operating lever; and the reversing lever is provided with the operating handle 13 extending outward, and the lowering block 14 extending inward and upward from its pivotal bearing. The lowering block is provided with the cam faces 15 and 16 co-operating respectively with the posts 17 and 18 on the sides of the pawls 8 and 9, for controlling the same in the action of lowering the lifting bar in a manner well known in 60 the art.

The coil of the spring 19 is mounted on the post 20 fixed on one side of the standard 2 adjacent to and above the lowering block 14; which spring has one end 21 secured to or stopped by the flange 2^a on the standard, and its other end 22 is elongated and extended downward as a finger in sliding engagement with the inner end 23 of the reversing lever, in which end is provided the 70 notch 24 for holding the spring finger from lateral displacement on the end of the lever.

By this construction and arrangement, it is evident that the lateral pressure of the elongated finger 22 against the inner end 23 80 of the reversing lever serves to hold the same upward, with the cam faces on the lowering block in the path of the posts on the sides of the pawls, for controlling the same in the reversing or lowering operation of 85 the jack, as shown in Fig. 1; or to hold the inner end of the reversing lever downward with the cam faces of the lowering block out of the path of the pawl posts, when rotated to such position by means of the handle 13 90 on the outer end of the lever, as shown in Fig. 2; which rotation is permitted by the sliding of the inner end of the reversing lever along the finger of the torsion spring.

And it is also evident that when the lowering block on the inner end of the reversing lever is held upward to bring its cam faces in the path of the pawl posts, the sliding contact of the finger of the controlling spring permits the intermittent movement 100 of the block required for a proper control of the pawls in their action in lowering the lifting bar.

The spring finger may be shaped with the reverse bends 25 and 26 in its shank, below 105 which the engaging portion may be formed substantially straight, as shown in Figs. 1 and 2, or the entire finger can be shaped as a flat curve 22^a, as shown in Fig. 3, without materially varying its sliding action in 110

holding and controlling the operation of the reversing lever.

I claim:

A lifting jack including an upright standard with a lifting bar operatively mounted therein having ratchet teeth on one side, an operating lever fulcrumed on the standard, a pawl pivoted to the standard and a pawl pivoted to the inner end of the operating lever operatively engaging the ratchet teeth, there being posts on the sides of the pawls, a reversing lever pivoted to the standard having a lowering block on its inner end

with cam faces which may be rotated into the path of the pawl posts, and a spring 15 mounted on the standard having an elongated laterally yielding spring abutment in sliding engagement with one end of the reversing lever for pressing the same in opposite directions for holding the lowering 20 block either in or out of the path of the pawl posts.

EDMUND C. BATES.
